(57) **CLAIM**

The ornamental design for a hand held pressure gauge, as shown and described.

DESCRIPTION

FIG. 1 is a front and right side perspective view of the hand held pressure gauge according to the invention.

FIG. 2 is a front elevation view of the hand held pressure gauge according to the invention.

FIG. 3 is a left side elevation view of the hand held pressure gauge according to the invention.

FIG. 4 is a right side elevation view of the hand held pressure gauge according to the invention.

FIG. 5 is a rear elevation view of the hand held pressure gauge according to the invention.

FIG. 6 is a top plan view of the hand held pressure gauge according to the invention; and,

FIG. 7 is a bottom plan view of the hand held pressure gauge according to the invention.

The broken lines showing portions of the hand held pressure gauge are for illustrative purposes only and do not form part of the claimed design.
